UNITED STATES PATENT OFFICE.

LEWIS T. BAKER, OF JACKSONVILLE, FLORIDA, ASSIGNOR TO HERTY TURPENTINE CUP COMPANY, OF JACKSONVILLE, FLORIDA.

TURPENTINE-GUTTER.

1,183,793.

Specification of Letters Patent. Patented May 16, 1916.

Application filed March 29, 1916. Serial No. 87,549.

To all whom it may concern:

Be it known that I, LEWIS T. BAKER, a citizen of the United States, residing at Jacksonville, in the county of Duval and State of Florida, have invented a new and useful Turpentine-Gutter, of which the following is a specification.

This invention relates to devices of that type known as turpentine gutters whereby the sap of a pine tree is properly collected and directed into a cup provided therefor.

One of the objects of the invention is to provide a turpentine gutter which can be easily and quickly attached to a tree in such a manner as to prevent any of the sap or gum from running down the tree behind the gutter.

A further object is to provide a device of this character which can be adjusted to fit trees of different sizes.

Another object is to provide simple and efficient means for holding the gutter to a tree, it being possible to easily remove the gutter when desired.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of a gutter embodying the present improvements. Fig. 2 is a side elevation thereof, a cup being shown in position and a portion of the hanger of the gutter being broken away. Fig. 3 is a section on line A—B Fig. 1. Fig. 4 is a section on line C—D Fig. 2.

Referring to the figures by characters of reference 1 and 2 designate opposed wings preferably formed of sheet metal and which are provided, at their inner corners, with projecting ears 3 disposed in lapped relation and through which ears extends a rivet 4 constituting a pivot. The outer edges of the wings are bent upwardly to form triangular flanges 5 which constitute guards to

prevent gum from pouring over the front edges of the wings.

Formed along the inner edges of the two wings are guides 6 produced by forming tongues at the inner ends of the wings and bending said tongues back under the respective wings and then folding the tongues to produce U-shaped guides, as shown particularly in Figs. 2 to 4 inclusive. It will be apparent that these guides converge backwardly when the two wings are out of alignment. The backwardly converging guides are adapted to engage the opposed converging edges of a wedging plate 7 which bridges the space between the wings and is provided, at its back end, with a hanger 8 the side edges of which are preferably curved rearwardly as shown at 9. Opposed angular ears 10 are struck forwardly from the hangers and are so shaped as to engage and support a cup a portion of which has been indicated at 11 in Fig. 2. This cup is the usual clay one, although it is to be understood that other forms of cups may be employed if desired. A short apron 12 extends downwardly from the front edge of the plate 7 and has an opening for the reception of a nail 13 which is also designed to extend through an opening 14 formed in the upper portion of the hanger 8. As will be seen by referring to Fig. 2, the wedging plate 7 is normally inclined when the hanger 8 is pressed against a tree.

In using a gutter a slight incision is first made in the tree, after which the wings 1 and 2 are pressed tightly against the cut portion of the tree so that the back edges of the wings will be embedded in the tree. The plate 7 is then thrust toward the tree and its inwardly converging side edges will press against the guides 6 so as to hold the wings firmly in position in engagement with the tree. A nail 13 is then inserted through the apron 12 and the opening 14 and forced into the tree, it being obvious that as this nail is driven into position its head will pull upon the apron and thrust the plate 7 still farther in a rearward direction, thereby securely locking the gutter in place so that the wings cannot become accidentally displaced until after the wedging plate has been pulled forwardly. With the parts assembled and mounted as described, the cup 11 can be placed in position and will

receive all of the sap draining from the wings 2 onto the exposed portion of the wedging plate 7. When it is desired to remove the gutter it is merely necessary to grip the head of the nail and withdraw the nail whereupon, by pulling forwardly on the wedging plate 7, the wings 1 and 2 will be free to swing forwardly out of the incision in the tree.

10 It will be seen that the entire structure is very cheap to manufacture, is simple and efficient and will not readily get out of order. It will adapt itself to trees of different diameters and when once secured in position 15 cannot become displaced relative to the tree unless the nail constituting the fastening means is withdrawn from the tree.

What is claimed is:—

1. A turpentine gutter including pivotally connected tree engaging wings, a wedging member engaging the inner end portions of the wings for holding them against relative movement in one direction, and a cup hanger depending from the wedging member.
2. A turpentine gutter including tree engaging wings movably connected, means insertible into engagement with the inner end portions of the wings for holding them against relative movement while in engagement with a tree, and a cup engaging element integral with said means.
3. A turpentine gutter including pivotally connected tree engaging wings, a wedging element insertible into engagement with said wings for holding them against movement

out of engagement with a tree, and a cup supporting hanger integral with said wedging element.

4. A turpentine gutter including pivotally connected tree engaging wings, guides along the inner edges of said wings, a wedging element insertible into engagement with the guides for folding the wings against relative movement in one direction, and a cup 45 engaging hanger depending from said element.

5. A turpentine gutter including pivotally connected tree engaging wings, guides at the inner ends of the respective wings, a wedging plate engaging the guides to hold the wings against relative movement in one direction, a cup supporting hanger depending from said wedging plate, said hanger having a fastener receiving opening.

6. A turpentine gutter including pivotally connected tree engaging wings, guides at the inner ends of the respective wings, a wedging plate engaging the guides to hold the wings against relative movement in one direction, a cup supporting hanger depending from said wedging plate, an apron depending from the outer end of the wedging plate, said apron and hanger having fastener receiving openings.

In testimony that I claim the foregoing as my own, I have hereto affixed my signature in the presence of two witnesses.

LEWIS T. BAKER.
